(57) **CLAIM**

The ornamental design for a trim tab actuator as shown and described.

DESCRIPTION

FIG. 1 is a perspective view of a trim tab actuator according to the design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The evenly dashed broken lines represent portions of the trim tab actuator that form no part of the claimed design. The dash-dot broken lines represent the boundaries of the claimed design and form no part of the claim.
